(57) **CLAIM**

The ornamental design for a lagging sheet as shown and described.

DESCRIPTION

FIG. 1 is a front and top perspective view of a lagging sheet showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top elevation view thereof;

FIG. 7 is a bottom elevation view thereof;

FIG. 8 is a partial enlarged view thereof according to broken quadrilateral "8" shown in FIG. 1;

FIG. 9 is a partial enlarged view thereof according to broken quadrilateral "9" shown in FIG. 1;

FIG. 10 is a partial enlarged view thereof according to broken quadrilateral "10" shown in FIG. 3;

FIG. 11 is a partial enlarged view thereof according to broken quadrilateral "11" shown in FIG. 4; and,

FIG. 12 is a partial enlarged view thereof according to broken quadrilateral "12" shown in FIG. 6.

The even spaced broken lines shown in the drawings depict portions of the article that form no part of the claimed design. The dash-dot-dot broken lines shown in the drawings illustrate the boundary of the portion shown enlarged in FIGS. 8 to 12. The dash-dot-dot lines shown in FIGS. 1 and 4-7 indicated a symbolic break in length. The appearance of any portion of the article between the dash-dot-dot lines forms no part of the claimed design.
